[57] CLAIM

The ornamental design for a basketball practice goal, as
 shown and described.

DESCRIPTION

FIG. 1 is a front elevational view of the basketball practice goal showing our new design;

FIG. 2 is an elevational view of one side of the goal, the
 other side being substantially identical thereto;

FIG. 3 is a rear elevational view of the device shown in
 FIGS. 1 and 2; and

FIG. 4 is a top plan view of the basketball practice goal.

*Fig. 1.**Fig. 2.**Fig. 3.**Fig. 4.*
